UNITED STATES PATENT OFFICE

HENRY HAROLD HOLMES AND ROBERT HAROLD ROBINSON, OF LEICESTER, ENGLAND,
ASSIGNORS TO WILDT AND COMPANY LIMITED, OF LEICESTER, ENGLAND, A BRITISH
COMPANY

THREAD-TRAPPER AND REVERSE-PLATING MECHANISM FOR KNITTING MACHINES

Application filed July 1, 1929, Serial No. 375,049, and in Great Britain August 30, 1928.

This invention consists in improvements in or relating to thread-trappers for knitting machines. Although in the form to be described hereinafter, the thread-trapper is designed for use with an improvement of the reverse-plating mechanism described in our copending application Ser. No. 375,048, filed of even date herewith, it is not necessarily limited thereto and may be usefully employed in conjunction with any type of circular knitting machine producing, for example, horizontally-striped fabric.

In the improved form of reverse-plating mechanism above referred to, there is combined with the relatively movable yarn-feeding guides, with or without the fixed guide as described in the prior specification, a movable yarn-presser or -deflector, and means to move it to hold a newly-introduced yarn or 20 yarns in position on the yarn-feeding guides while a replaced yarn or yarns is or are withdrawn. A "replaced" yarn is one that has been used in the knitting operation and is withdrawn in favour of a newly-introduced 25 yarn to alter the patterning effect.

A yarn-trapper according to the invention comprises relatively movable jaw-plates with an intermediate plate or plates between them, which latter is or are free to move away 30 from the jaw-plates (and from one another if more than one intermediate plate is provided) when the jaw-plates are opened apart. Conveniently, each such intermediate plate is guided by one or more rods or like members which serve to guide the movements of the jaw-plate or plates.

The trapper may be, and preferably is, combined with a movable yarn-finger which is operatively connected with a movable jaw-plate so as to move endwise in company therewith, and means is also provided to move the 40 yarn-finger in a transverse direction to guide the yarn between the jaw-plates. In one example, the movable yarn-finger is associated 45 with deflecting means whereby endwise movement of the finger automatically effects its transverse movement as, for example, by means of a guide-slot in the finger engaging a fixed pin.

50 In some forms of knitting machine to

which the present invention is applicable, the trapper and the yarn-feeders are necessarily so disposed relatively to the needles that after a yarn has been trapped and when the feeder is brought into the feeding position, 55 the yarn does not lie in a position in which it can be taken by the needles. In such circumstances, there is preferably employed in combination with the trapper, a movable yarn-presser or -deflector and means to move 60 it to a position in which it will hold a newly-introduced yarn or yarns so that they can be taken by the needles. The yarn-presser may be disposed between the feeder and the 65 trapper.

In order that the present invention may be more clearly understood, a preferred embodiment will now be described with the aid of the accompanying drawings, in which—

Figure 1 is an under plan view of a thread-trapper and severing device according to the invention;

Figure 2 is a side elevation of the trapper shown in Figure 1, viewed from above in that figure;

Figure 3 is a section on the line 3—3 of Figure 1;

Figure 4 is a side elevation showing a plurality of yarn-feeders and a yarn-presser or -deflector associated with them;

Figure 5 is a view of the parts shown in Figure 4 looking from the left-hand side thereof;

Figure 6 is a schematic view showing one feeder in and one out of use and illustrating 85 the relative positions of the trappers, feeders and yarn-presser;

Figure 7 is a composite plan view looking down on the latch-ring to illustrate the relative positions of the several parts illustrated 90 in Figure 6, and

Figure 8 is a schematic view showing the 95 yarn-trapper applied to a knitting machine employing both dial- and cylinder-needles.

Like reference numerals indicate like parts in all the figures of the drawings.

The trapping device illustrated in Figures 1 to 3 comprises vise-like jaws 11 and 12 of which the jaw 12 is fixed on the latch-ring post 130 by means of a bracket 14, as shown 100

- in Figure 7. Guide-pins 15, secured to the fixed jaw, extend through holes in the movable jaw 11 to guide the latter and also to guide one or more intermediate plates 16.
- 6 A spring 17 on one of the guide-rods 15 (or on each of them, if preferred) tends always to maintain the jaws closed together. The movable jaw is actuated by means of an end-wise-movable plunger 18 which carries a finger 19. The end of the latter, when the plunger is moved to the left in Figures 1 to 3, will engage with the adjacent face of the movable jaw and open it against the compression-spring 17.
- 10 15 A pin 20, extending laterally from the plunger 18, has pivotally mounted on it a yarn-finger 21 which will move in company with the movable plunger 18 and consequently also with jaw 11. The yarn-finger has a downwardly-extended lip 22 which, as it is moved forwardly, will engage beneath the yarn or yarns to be trapped. The finger 21 also has in it a cam in the form of a guide-slot 23 which engages a relatively fixed pin 24 so that after the finger 21 has been moved forwardly beneath the yarns to be trapped, its lip will be raised upwardly to lift the yarn or yarns in between the jaw-plates and at the time to prevent those yarns which are still to be retained in the trapper and the newly-introduced yarns from falling out from between the plates before the latter are closed. The intermediate plate or plates 16 are for the purpose of better separation of the yarns. The latter will pass, by chance, between one or the other of the intermediate plates or between one of them and a jaw-plate.
- 20 25 30 35 Associated with the trapper is also a cutter comprising a fixed knife-blade 25 and a movable blade 26 swinging about the axis of a pin 27. Alternatively, the movable blade may be slidable in relation to the fixed knife-blade. Endwise movement imparted to another slider 28, parallel with the slider 18, of which the forward end 29 engages and moves with the cutting blade 26, serves to operate the cutter.
- 40 45 50 The sliders 18 and 28 are operated in sequence by means of an adjustable abutment indicated at 30 (Figure 3) between which and the sliders there is relative rotation about the axis of the needle-cylinder.
- 55 60 The abutment 30 is adjusted from the inoperative position illustrated into a position in which it will engage the sliders at appropriate times. The sequence of operation will be as follows:
- When it is desired to replace a yarn or yarns by another yarn or yarns for a change of pattern, a new yarn will be introduced by the actuation of a yarn-feeder, to be referred to later.
- Simultaneously, the feeder for each yarn that is to be released will carry its yarn away from the needles into a position to enter between the jaw-plates. That is to say, it will be brought immediately beneath the trapper-jaws 11 and 12. The trapper is at this point opened by engagement of the adjustable abutment 30 with the slider 18.
- A sloping surface 31 on the movable jaw 11 ensures the guiding of the yarn or yarns into the space between the opened jaws. During the opening of the latter, the yarn-finger 21 moves beneath the yarn or yarns that are about to enter the jaws so as to lift each such yarn in between the trapper-jaws or intermediate plates. Meanwhile, a newly-introduced yarn will have been withdrawn from the jaws. The opening and closing of the latter is a quick operation, and immediately following the actuation of the slider 18 (there being just sufficient time interval to allow the yarns to "settle" in place), the shear-knife 26 is actuated by engagement of the abutment 30 with the slider 28. Each newly-introduced yarn is thereby severed.
- In one embodiment of the invention as illustrated in Figures 4 to 7, the yarns are shown as supplied to the needles by means of interchangeable yarn-feeders 32. Each such feeder is pivoted to turn about a pin 33 and may supply a single yarn, or it may supply more than two yarns, but in itself it constitutes no part of the present invention and constitutes part of the subject-matter of our copending application Ser. No. 375,048, above referred to.
- Associated with the yarn-feeders 32 is a yarn-presser or -deflector 33 in the form of an open or bow-like frame pivotally mounted at 34 at a position between the trapper device and the yarn-feeders 32. This is clearly shown in Figures 6 and 7. As will be understood from the co-pending application above referred to, in the device illustrated in detail in Figures 4 and 5 all the yarn feeders are shown in their raised non-feeding positions. The yarn-presser 33 is actuated to move about its pivot 34 after the yarn-feeder of a yarn to be introduced has been swung downwardly into the feeding position. The design of the parts is such that the movement of the presser 33 follows up that of the yarn-feeder 32 so that the presser 33 will come in behind the yarns to hold that one which has been newly introduced in a position in which it can be taken by the needles. It is immaterial to the present invention what form of mechanism is employed for actuating the yarn-presser 33, and the need for this presser only occurs in cases in which the movements of the yarn-feeders are such as to bring their yarns into a position over the heads of the needles without bringing them into a position such that the needles can take the newly-introduced yarn. In other words, in the example illustrated the lie of the newly-introduced yarn will be in the required direc-

tion, but it is necessary to press the yarn downwardly to bring it to a height at which the descending needles can engage and take it into their hooks at the knitting position.

5 In usual practice, the relation between the trapper, feeder and needles is such that the trapper intercepts the yarn-path between the feeder and the needles when the feeder is being swung out of action. The feeders are so placed, relatively to the needles, that the mere fact of their being put back into position will bring the yarns into the feed position. In such a case, it will be unnecessary to provide the yarn-presser 33, and the latter will only be necessary in cases in which the yarns are not automatically, when reintroduced by their feeders, brought into the feed position.

20 In the example illustrated in Figures 4 to 7, the feeders do not bring the yarns directly to the needles but to a reverse-plating mechanism comprising yarn engaging reversing fingers 36 and 37 as will be understood by reference to the co-pending application previously mentioned, and consequently the yarn-presser 33 is required; and it may be equally required for other constructions of machine in combination with the trapper device described. An example, however, of conditions 25 in which the yarn-presser is not required is given schematically in Figure 8. The machine illustrated here is intended to be a rib-machine employing cylinder-needles such as 40 and dial-needles such as 41. The yarn-feeders are diagrammatically illustrated at 30 42 and 43, whereof the feeder 42 is in the feed position. The feeder 43 has been moved to bring its yarn in between the trapper-jaws. The trapping device is illustrated as viewed 35 end-on from the left of Figure 3 with the device tilted so that the sloping surface 31 is presented to the yarn that is to enter it.

40 It will be understood, of course, that the invention is not limited to the particular form of yarn-presser illustrated herein, nor to the particular manner in which it is moved, as any pressing device, which will operate in the manner and for the purpose above described upon a yarn that has been brought 45 by its feeder into a position for supplying the yarn to the needles, may be employed.

We claim:

1. For a knitting machine, a yarn-trapper comprising in combination relatively separable jaw-plates, and at least one intermediate plate between them that is free to separate from the jaw-plates when the latter are opened apart thereby affording a plurality of gaps into any one of which a yarn can pass as it is withdrawn.

2. For a knitting machine, a yarn-trapper comprising in combination separable jaw-plates, a plurality of intermediate jaw-plates between them, each of which is free to separate from the jaw-plates and from one an-

other when the jaw-plates are opened apart thereby affording a plurality of gaps into any one of which a yarn can pass as it is withdrawn.

3. For a knitting machine, a yarn-trapper comprising in combination relatively separable jaw-plates, at least one intermediate plate between them that is free to separate from the jaw-plates when the latter are opened apart thereby affording a plurality of gaps 70 into any one of which a yarn can pass as it is withdrawn, and means to guide the movement of the intermediate plate.

4. For a knitting machine, a yarn-trapper comprising in combination relatively separable jaw-plates, at least one intermediate plate between them that is free to separate from the jaw-plates when the latter are opened apart thereby affording a plurality of gaps 80 into any one of which a yarn can pass as it is withdrawn, and a guide to guide the movement of the intermediate plate and also the relative movement of the jaw-plates as they are separated.

5. For a knitting machine, a yarn-trapper comprising in combination relatively separable jaw-plates, at least one intermediate plate between them that is free to separate from the jaw-plates when the latter are opened apart thereby affording a plurality of gaps 90 into any one of which a yarn can pass as it is withdrawn, and a movable yarn-finger that, as the jaw-plates are separated, is movable in a direction transverse to the direction of separation in order to guide the yarn into one 95 of the gaps between the opened jaw-plates.

6. For a knitting machine, a yarn-trapper comprising in combination relatively separable jaw-plates, at least one intermediate plate between them that is free to separate from the jaw-plates when the latter are opened apart thereby affording a plurality of gaps 105 into any one of which a yarn can pass as it is withdrawn, and a movable yarn-finger which, as the jaw-plates are separated, is movable both transversely to the direction of separation and also in the direction of separation of the jaw-plates in order to guide the yarn 110 into one of the gaps between the opened jaw-plates.

7. For a knitting machine, a yarn-trapper comprising in combination two jaw-plates, one of which is relatively fixed and the other is movable towards and away from the companion plate, at least one intermediate plate between them that is free to separate from the jaw-plates when the latter are opened apart thereby affording a plurality of gaps 120 into any one of which a yarn can pass as it is withdrawn, a movable yarn-finger, and means operatively connecting said finger with the movable jaw-plate in such a manner as to move the finger endwise in the direction of the separation of the plates, and also at the same time to raise it in order to pass beneath 125 130

the yarn and guide it into one of the gaps between the opened jaw-plates.

8. For a knitting machine, a yarn-trapper comprising in combination two jaw-plates, one of which is relatively fixed and the other is movable towards and away from the companion plate, at least one intermediate plate between them that is free to separate from the jaw-plates when the latter are opened apart thereby affording a plurality of gaps into any one of which a yarn can pass as it is withdrawn, a yarn-finger movable endwise in company with the movable jaw-plate to advance with the latter as it is separated from the relatively fixed plate, and means also to guide the finger during its endwise movement so as to cause the finger to move across the gap between the jaw-plates transversely to the direction of separation thereof.

9. For a knitting machine, a yarn-trapper comprising in combination two jaw-plates, one of which is relatively fixed and the other is movable towards and away from the companion plate, at least one intermediate plate between them that is free to separate from the jaw-plates when the latter are opened apart thereby affording a plurality of gaps into any one of which a yarn can pass as it is withdrawn, a movable yarn-finger, means operatively connecting the latter with the movable jaw-plate whereby the finger is moved endwise in company with the movable jaw-plate in the direction of separation of the jaw-plates, and deflecting means operable automatically on the yarn-finger during its endwise movement to move it across the gap between the jaw-plates transversely to the direction of separation thereof.

10. For a knitting machine, a yarn-trapper comprising in combination two jaw-plates, one of which is relatively fixed and the other is movable towards and away from the companion plate, at least one intermediate plate between them that is free to separate from the jaw-plates when the latter are opened apart thereby affording a plurality of gaps into any one of which a yarn can pass as it is withdrawn, a movable yarn-finger operatively connected with the movable jaw-plate to move endwise with the latter, and a cam and cooperating projection to ride thereon, one of which elements is associated with the finger and the other with the relatively fixed part, whereof the shape of the cam is such as to permit the finger first to move endwise with the movable jaw-plate and then to be moved transversely to that direction across the gap between the jaw-plates for the purpose described.

11. For a knitting machine, a yarn-trapper comprising in combination two relatively separable jaw-plates, a movable yarn-finger operatively connected with the jaw-plates so that as they are separated the finger is projected across the gap in the direction of separation, and is subsequently moved into the gap transversely of the direction of separation.

12. For a knitting machine, the combination of a yarn-trapper having relatively separable jaw-plates and at least one intermediate plate between them that is free to separate from the jaw-plates when the latter are opened apart thereby affording a plurality of gaps into any one of which a yarn can pass as it is withdrawn, a thread-cutter, and two endwise-movable sliders arranged substantially parallel with one another but spaced apart in the direction of the length of the needle-bed, one said slider being operatively connected to, and serving as the operating member for, the movable jaw-plate, and the other slider operatively connected with, and serving to actuate, the cutter.

13. For a knitting machine, the combination of a yarn-trapper comprising relatively separable jaw-plates and at least one intermediate plate between them that is free to separate from the jaw-plates when the latter are opened apart thereby affording a plurality of gaps into any one of which a yarn can pass as it is withdrawn, a thread-cutter, an abutment between which and the trapper and cutter there is relative movement in the direction of the length of the needle-bed, elements associated with the movable jaw-plate and the cutter to be engaged with the abutment to be actuated thereby, and so arranged that the abutment first engages with the jaw-opening element and afterwards with the cutter-operating element.

14. For a knitting machine, a yarn-trapper comprising in combination relatively separable jaw-plates, at least one intermediate plate between them that is free to separate from the jaw-plates when the latter are opened apart, thereby affording a plurality of gaps in any one of which a yarn can pass as it is withdrawn, means to separate the jaws at desired times, a thread-cutter, and a cutter-actuating member which is operated independently of the jaw-separating means by movement in a direction parallel with the direction of separation of the jaw-plates.

In testimony whereof we have signed our names to this specification.

HENRY HAROLD HOLMES.
ROBERT HAROLD ROBINSON.
